Primary Examiner — Philip S Hyder*(74) Attorney, Agent, or Firm* — Muncy, Geissler, Olds & Lowe, P.C.(57) **CLAIM**

The ornamental design for a hand tool handle as shown and described.

DESCRIPTION

FIG. 1 is a perspective view of a hand tool handle showing the claimed design;

FIG. 2 is a front view thereof;

FIG. 3 is a left side view thereof;

FIG. 4 is a top plan view thereof;

FIG. 5 is a bottom plan view thereof;

FIG. 6 is a front view showing that the hand tool handle of the present design is attached with a tool bit;

FIG. 7 is a front view thereof, showing that a retractable handle of the hand tool handle positioned in an extended position; and,

FIG. 8 is a front view thereof, showing that a retractable handle of the hand tool handle positioned in a second extended position.

The broken line showing of the screwdriver bit in FIG. 6 is provided for purposes of environment and forms no part of the claimed design.
